Primary Examiner — T. Chase Nelson*Assistant Examiner* — Kathleen M Sims(74) *Attorney, Agent, or Firm* — James E. Howard; Andre Pallapies(57) **CLAIM**

The ornamental design for a resilient dishwasher accessory, as shown and described.

DESCRIPTION

FIG. 1 is a front perspective view of a resilient dishwasher accessory showing my new ornamental design;

FIG. 2 is a front view thereof, with the rear view being identical;

FIG. 3 is a top view thereof;

FIG. 4 is a bottom view thereof;

FIG. 5 is a left side view thereof with the right side view thereof being a mirror image thereof;

FIG. 6 is a left side view thereof in a position in which the dishwasher accessory is assembled or attached to a dishwasher rack; and,

FIG. 7 is a perspective view thereof in the position where the dishwasher accessory is assembled or attached to the dishwasher rack.

The broken lines show surrounding structure or environment and do not form part of the claimed design. The dotted lines in FIGS. 1-7 show the boundary between claimed and unclaimed subject matter and form no part of the claimed design.
